UNITED STATES PATENT OFFICE.

GEORGE F. McADAMS, OF BROOKLYN, NEW YORK.

PAPER-RULING MACHINE.

1,302,571.

Specification of Letters Patent.

Patented May 6, 1919.

Application filed July 5, 1917. Serial No. 178,743.

To all whom it may concern:

Be it known that I, GEORGE F. McADAMS, a citizen of the United States, and resident of the borough of Brooklyn, in the city and 5 State of New York, have invented a new and useful Improvement in Paper-Ruling Machines, of which the following is a specification.

My invention relates to improvements in 10 the construction, form, arrangement and operation of the several parts of a paper ruling machine of that type in which the paper is caused to travel first in one direction and then in a direction at substantially right angles to obtain the cross ruling of the paper; whereby the paper may be handled at a greater speed than heretofore without buckling; and in which a poorer quality of 15 paper may be successfully handled.

20 A practical embodiment of my invention is represented in the accompanying drawings, in which—

25 Figure 1 represents a plan of so much of a ruling machine as includes my invention, and

Fig. 2 represents the same, partly in end elevation and partly in longitudinal vertical section.

30 The endless carrier 1 feeds the sheets onto the endless carrier 3, their adjacent rolls being denoted by 2 and 4, respectively. The tapes or cords of the carrier 3 pass around two rolls 5 and 6 and around a roll 7, so arranged that the portion of the carrier between the rolls 6 and 7 is in a plane slightly 35 below the portion of the carrier between the rolls 4 and 5. A table 8 forms a horizontal extension of the carrier 3 from the roll 7 and beyond the plate is a sheet stop comprising a vertical portion 9 and a horizontal portion 10, which sheet stop is carried by 40 brackets 11, uprising from the machine frame, the said horizontal portion 10 forming an extension of the table 8 in a slightly 45 lower horizontal plane. The table 8 may be supported by the brackets 11 and brackets 12, the brackets 12 serving also as a support for the roll 7.

An endless cross carrier comprises two 50 cross belts 13 and 14, the belt 13 passing around a pulley 15 and the roll 16, the upper portion extending across the depressed portion of the carrier 3. The belt 14 passes around a pulley 17 and the roll 16, the upper portion traveling on the horizontal portion 10 of the sheet stop.

To adapt the cross belts 13 and 14 to different sized sheets, the belt 13 may be moved laterally along the roll 16 at one end of the carrier, the belt at the other end of the carrier being movable laterally by adjusting the position of the pulley 15 lengthwise of the endless carrier 3.

60 This may be done by moving the brackets 18, which support the rolls 5 and 6 and the pulley 15, along the frame.

A series of diagonally arranged rollers 19 may be loosely mounted in suitable bearings in a frame 20 so that the rollers will rest on the sheet near its advance edge as it is fed 70 into position over the table 8 and cross belts 13 and 14 against the sheet stop 9. The cross carrier will feed the sheets to an endless carrier 21, the tapes of which pass around the roll 16 at that end of the carrier. 75

The sheet along one edge will be firmly held by the weight of the diagonal rollers 19 on the belt 14, the belt being firmly supported by the horizontal portion 10 of the sheet stop; and will rest along its rear edge 80 on the belt 13. Intermediate said edges, the sheet will rest on the table 8, thus permitting the ready feeding off of the sheets onto the carrier 21, with a minimum amount of friction. It will also be seen that when the 85 sheet is sliding along the table 8, there is insufficient air underneath the sheet to allow it to buckle or become distorted.

Any suitable means may be employed to 90 drive the several carriers, such means in the present instance, including the two cross shafts 22, 23, their step pulleys 24, 25, and belt 26; the longitudinal shaft 27, its geared connection 28, 29, with the shaft 23; the pulleys 30, 31, on the shaft 27 and their driving belts 32, 33; the belt 33 leading around a pulley 34 on the shaft of the roller 16; and the pulley 35 on the shaft 22, its belt 36 leading around the pulleys 37, 38, on the shafts of the rolls 2, 4, and the idler pulley 39. 95

100 It is evident that changes may be resorted to in the form, construction and arrangement of the several parts without departing from the spirit and scope of my invention; hence I do not wish to limit myself strictly to the 105 structure herein set forth, but

What I claim is:—

1. In a ruling machine, an endless carrier arranged in a substantially horizontal plane for carrying the sheets in one direction, a 110 horizontally arranged table forming an extension of said endless carrier, and a hori-

zontally arranged endless cross carrier arranged in a substantially horizontal plane for carrying the sheets in another direction comprising two belts located along opposite 5 sides of said table.

2. In a ruling machine, an endless carrier for carrying the sheets in one direction, said carrier having a depressed portion, a table forming an extension of said depressed portion, and an endless cross carrier for carrying the sheets in another direction comprising 10 two belts located along opposite sides of the table.

3. In a ruling machine, an endless carrier for carrying the sheets in one direction, said carrier having a depressed portion, a table forming an extension of said depressed portion, and an endless cross carrier for carrying the sheets in another direction comprising 15 two belts located along opposite sides of the table, one of said belts passing over the depressed portion of the first-named carrier.

4. In a ruling machine, an endless carrier for carrying the sheets in one direction, said carrier having a depressed portion, a table forming an extension of said depressed portion, a cross carrier comprising two belts, one located along said depressed portion and the other beyond the table and in substantially 20 the same plane therewith, a sheet stop beyond said last-named belt, a rigid horizon-

zontal support for said last-named belt, and rollers adapted to rest on said belt.

5. In a ruling machine, an endless carrier for carrying the sheets in one direction, said carrier having a depressed portion, a cross carrier for carrying the sheets in another direction comprising belts, one belt being located along said depressed portion and means for adjusting said last-named belt 35 laterally and for adjusting the length of the depressed portion of the first-named carrier to adapt the same to sheets of different sizes.

6. In a ruling machine, an endless carrier for carrying the sheets in one direction, said carrier having a depressed portion, a cross carrier for carrying the sheets in another direction comprising belts, one belt being located along said depressed portion, means 40 for adjusting said last-named belt laterally and for adjusting the length of the depressed portion of the first-named carrier to adapt the same to sheets of different sizes, and a table located between said belts forming an 45 extension of said depressed portion of the first-named carrier.

In testimony, that I claim the foregoing as my invention, I have signed my name this 26th day of June 1917.

GEORGE F. McADAMS.
